ATTORNEY

UNITED STATES PATENT OFFICE.

JAMES E. HILLS, OF BROOKLYN, NEW YORK.

DESIGN FOR A LINK CUFF-BUTTON.

SPECIFICATION forming part of Design No. 24,722, dated October 1, 1895.

Application filed June 1, 1895. Serial No. 651,412. Term of patent 14 years.

To all whom it may concern:

Be it known that I, JAMES E. HILLS, residing at the city of Brooklyn, State of New York, have invented a Design for Link Cuff-Buttons, 5 of which the following is a specification.

Reference is to be had to the accompanying drawings, illustrating my design, and in which—

Figure 1 is a plan view of a link cuff-button embodying the design, and Fig. 2 is a front elevation thereof.

My design consists of the substantially straight shank portion 1 of the button as combined with or viewed in connection with

the angularly-disposed heads 2 3, said heads 15 leaning toward each other from the rear toward the front of the button and connected to the opposite ends of the shank at points where their edges are nearest together.

What I claim is— 20

The design for a link cuff-button substantially as herein shown and described.

In testimony whereof I affix my signature in the presence of two witnesses.

JAMES E. HILLS.

Witnesses:

R. P. HESS,
P. N. TURNER.
